UNITED STATES PATENT OFFICE.

LEONARD G. QUACKENBOSS, OF CHICAGO, ILLINOIS.

DISPLAY-HOLDER.

1,341,822.

Specification of Letters Patent.

Patented June 1, 1920.

Application filed June 30, 1917. Serial No. 178,014.

To all whom it may concern:

Be it known that I, LEONARD G. QUACKENBOSS, a citizen of the United States, residing at Chicago, in the county of Cook and

5 State of Illinois, have invented new and useful Improvements in Display-Holders, of which the following is a full, clear, concise, and exact description, reference being had to the accompanying drawing, forming

10 a part of this specification.

My invention relates to display-holders.

Among the objects of my invention is to provide an improved display-holder movable through an opening in the building 15 construction whereby the holder may be placed on the outside of the building for display purposes, or readily inclined toward the inside of the building for cleaning or removal from the opening or for other purposes.

20 A further object of my invention is to provide an improved display-holder of the character indicated which can be detachably connected with ordinary window openings and shall be substantially coextensive 25 with the opening in the building construction. A further object of my invention is to provide a display-holder of the character indicated which can be used with window construction comprising movable sash.

30 A further object of my invention is to provide an improved display-holder of the character indicated which will not interfere with the usual and ordinary manipulation of the sash of the window. A further ob-

35 ject is to provide an improved display-holder of the character indicated which can be readily applied to windows of existing types without materially defacing the construction. A further object of my invention

40 is to provide an improved display-holder of the character indicated which will not interfere materially with the light coming through the window. A further object of my invention is to provide an improved dis-

45 play-holder of the character indicated which may be made practically weather, water and dust-proof in construction. A further object of my invention is to provide a display-holder of the character indicated

50 which tilts and slides about a support intermediate the upper and lower ends of the opening. An intermediate frame may be provided into which the display-holder may, by any convenient means, be rotated to re-

55 verse the holder for cleaning, etc. Further objects will appear from the detailed de-

scription to follow and from the appended claims.

In the drawings, in which several embodiments of my invention are shown—

60 Figure 1 is a front elevation of a building construction showing my improved display-holder in connection therewith;

Fig. 2 is a vertical section substantially on the line 2—2 of Fig. 1;

65 Fig. 3 is a vertical section on the line 3—3 of Fig. 1, the display-holder being removed;

Fig. 4 is a fragmentary vertical section on the line 4—4 of Fig. 3;

70 Fig. 5 is a side elevation of the display-holder, parts being broken away to show the interior construction;

Fig. 6 is a horizontal section on the line 6—6 of Fig. 1;

75 Fig. 7 is a horizontal section on the line 7—7 of Fig. 1;

Fig. 8 is a vertical section of a building construction showing another form of my improved display-holder in connection 80 therewith;

Fig. 9 is a vertical section on the line 9—9 of Fig. 8;

Fig. 10 is a vertical section of a building construction showing still another form of 85 my improved display-holder in connection therewith;

Fig. 11 is a section on the line 11—11 of Fig. 10;

Fig. 12 is a front elevation of another 90 form of my invention showing a lattice construction and a casement-window;

Fig. 13 is a vertical section on the line 13—13 of Fig. 12;

Fig. 14 is a section on the line 14—14 of 95 Fig. 13; and

Fig. 15 is a fragmentary horizontal section on the line 15—15 of Fig. 12.

Referring to the drawings in detail, and first to the form of Figs. 1 to 7, inclusive, 100 the building construction may be of any suitable or usual construction comprising a vertical wall having an opening therein in which is placed a window construction including as here shown a window-frame 10 105 with upper and lower sash 11 and 12 slidably mounted in the window-frame.

The display-holder 13 may be substantially co-extensive with the window opening and is movable from the position outside of the window and in front thereof (as shown in full lines in Fig. 2) in posi-

tion to display the articles contained therein, to a position in which it can readily be removed from the opening or in which position the exterior may be accessible for cleaning, etc.

For directing the display-holder in its movement from its display position through the opening in the window, a pair of supports 14 are secured on opposite sides of the window-frame, on the upper edge 15 of which the display-holder tilts and slides inwardly from its display position through the window opening.

The display-holder 13 may be of any suitable outline, form, construction and material or combination of materials, such as wood, metal, glass, screening, etc. As here shown it is in the nature of a show-case, having glass front 16 and glass sides 17 and wooden bottom 18 and top 18^a. However, other suitable material, as above stated, may be used.

The supports here shown are of channel form, as shown in Fig. 7, and an angle member 19 is secured to the rear edge of the sides 17 of the display-holder, the lip 20 of which enters the channel in the channel member 14 when the holder is in display position, to form a suitable joint which will be substantially dust and waterproof. The upper portion also of the show-case 13 may be provided as here shown with an angle member 21 secured to the rear edge of the sides 17 which coöperates with a channel member 22 secured to the upper portion of the sides of the window-frame, as shown in Fig. 6, to form a suitable joint similar to the joint formed by the members 19 and 14. If required for strength, stiffness or security, the supports 14 and the channels members 20 may each have a leg extending on the inner face of the hanging stile 22^a of the window-frame, and may be secured to the hanging stile if desired, as shown in Figs. 6 and 7.

For securing the holder 13 in the display position, a sliding bolt-latch 23 (Fig. 2) may be secured to the lower edge of the display-holder, the locking bolt 24 being, as here shown, positioned to enter an opening in the window-sill 25 to retain the display-holder in display position.

In order to retain the upper portion of the holder 13 snugly, a screw 26 may, as here shown, be threaded into a plate 27 secured to the upper edge of the holder 13, as shown in Fig. 2. As shown in Fig. 4, the lower edge of the channel member 22 is notched at 27^a to afford clearance for the lip 28 of the angle member 21 when the holder 13 is in tilted position.

The operation of this form of my device as here shown is as follows: Assuming that the display-holder 13 is in the position shown in full lines in Fig. 2 and it is de-

sired to move the holder through the window opening into the room to clean the holder or for any other purpose, the lower sash 12 is raised, the sliding bolt-latch 23 is operated to release the bolt 24 from the opening in the window-sill, and the lower end of the holder 13 is drawn inwardly, the holder tilting about the upper edge 15 of the supports 14. After the lower edge of the holder 13 is clear of the window-sill, the holder may be slid inwardly, the angle member 21 during the sliding movement sliding on the upper edge 15 of the supports 14. By this combined tilting and sliding movement the holder may be drawn as far into the room as desired or may be entirely removed from the opening. To move the holder from its position inside of the room to its display position, the reverse of the above takes place, the holder being slid outwardly on the supports 14 until the supports are substantially underneath the middle portion of the holder 13 when the holder is tilted about the upper edge 15 of the supports 14 to the position shown in full lines in Fig. 2, when the latch-bolt 24 is in position to enter the opening in the sill 25 and the screw 26 is in position to be screwed into the member 27.

In the form of my invention shown in Figs. 8 and 9 the display-holder 30 has secured to the rear edge thereof two laterally-extending flanges 31, one on each side of the display-holder, each flange 31 having a bend 32 therein intermediate its length, which rests on the upper edge 33 of the support 34 when the display-holder is tilted. The upper portions of the flanges 31 engage the upper sealing strips 35 which form a stop for the display-holder and with which the display-holder forms a close connection. Any suitable means similar to those shown in connection with Figs. 1 to 7 may be used for holding the display-holder in display position.

In this form of the display-holder the bend 32 prevents the display-holder from slipping down along the support 34 when the holder is tilted, but it has what may be considered a disadvantage, in that when it is attempted to slide the display-holder inwardly after it has been tilted for the lower edge to clear the window-sill, the bend 32 resists an inward pull on the holder.

The operation of this form of my display-holder is substantially the same as the operation of the form shown in Figs. 1 to 7, inclusive.

In Figs. 10 and 11 I have shown my improved display-holder provided with anti-friction bearing means for guiding the display-holder in its movement from its display position to its position for washing, etc.

In this form the display-holder 36 is provided at its rear edge with two laterally-

extending flanges 37, one on each side of the display-holder, each of which flanges 37 co-operates with upper and lower anti-friction rollers 38 and 39 which are mounted in 5 suitable bearings 40 and 41, respectively, secured to the supports 42 and 43, respectively, at the sides of the window-frame.

In this form of my device when the display-holder has been tilted far enough so 10 that its lower edge will clear the windowsill, the holder may be pulled inwardly, the flanges 37 engaging the rollers 38 and 39 to lessen the friction.

The operation of this form of my device 15 is substantially the same as the operation of the forms previously described.

In Figs. 12 to 15, inclusive, I have shown my invention in connection with a window-box 44 provided with a lattice framework 20 45 and pivotally mounted at 46 on the rectangular frame 47. This rectangular frame is provided with laterally-extending flange members 48 for engagement with the strips 49 which are secured to the parts 50 of the 25 window-frame. The sections 51 of the casement window are mounted to swing on hinges 52 secured to the window-frame.

In the use of this form of my invention 30 the casement window 51 may be opened, the latch 53 may be operated to release the window-box 44 and lattice 45 for swinging movement about the pivot 46, and the window-box may be swung on the pivot 46 in order to obtain access to the window-box. 35 Also, if desired after opening the casement window, the lower end of the frame 47 may be tilted inwardly, the flange 48 resting on the strips 49 and the frame 47 with the window-box 44 and latticework 45 may be 40 drawn downwardly and inwardly.

In all of the forms of the device the display-holder or show-case can be readily attached to existing types of window construction without interfering with the operation 45 of the windows and without materially defacing the windows, and without materially interfering with the light from the windows.

In all of the forms of my invention shown 50 the display-holder can be readily swung from its position outside of the window to a position inside of the window for cleaning, for removal from the opening, etc.

While I have shown but four embodiments 55 of my invention, it admits of various modifications which will readily suggest themselves to those skilled in the art, and, as it is evident that certain modifications or changes may be made in the structure of my invention without departing from the 60 spirit thereof, I therefore desire not to be limited to the construction here shown, the scope of my invention being defined in the appended claims.

When required, and as shown in Figs. 12 65 to 15, inclusive, convenient stops 52^a may

be secured to the flanges 48 in position to engage the upper edges of the strips 49 to limit the inward movement of the frame 47 to prevent it from slipping off the strips 49.

If required, top or bottom ventilators 70 with means for closing may be placed in the casing surrounding the display-holder as most convenient, as indicated at 53 in Fig. 10.

What I claim as new and desire to secure 75 by Letters Patent of the United States is:

1. The combination with a building construction having an opening therein lying in a substantially vertical plane, of a holder movable through said opening, and a combined guide and support located intermediate the upper and lower edges of said opening, on which said holder tilts and slides, for guiding said holder in its movement through said opening, so that the upper 80 edge of said holder swings outwardly and the lower edge of said holder swings inwardly to clear the lower edge of said opening, and then slides inwardly through said opening, said holder being provided with 85 longitudinally-extending slide portions for engagement with said combined guide and support.

2. The combination with a building construction having an opening therein lying in 95 a substantially vertical plane, of a holder movable through said opening, and a combined guide and supporting means for said holder, for guiding said holder in its movement through said opening, so that its upper edge swings outwardly and its lower edge swings inwardly, said combined guiding and supporting means comprising two supports, one located adjacent each side of 100 said opening, intermediate the upper and 105 lower edges of the openings.

3. The combination with a building construction having an opening therein lying in a substantially vertical plane, of a holder movable through said opening, and combined guiding and supporting means for guiding said holder in its movement through said opening, so that the upper edge of said holder tilts outwardly and the lower edge of 110 said holder swings inwardly, and so that the holder then slides inwardly through said opening, said guiding and supporting means comprising two members, one located adjacent each edge of said opening, said holder being provided with two elongated slide 115 members, one located at each side thereof, for engaging said guiding and supporting members.

4. The combination with a building construction having an opening therein lying 125 in a substantially vertical plane, of a sliding sash for closing the upper portion of said opening, a holder movable through said opening beneath the lower edge of said sash, and a combined guide and support for said 130

holder in its movement through said opening, on which said holder tilts so that its upper portion swings outwardly away from said sash and its lower portion swings inwardly through the opening beneath the sash, the upper portion of said holder being located above the lower edge of said sash.

5. The combination with a building construction having an opening therein lying in a substantially vertical plane, of a sliding sash for closing the upper portion of said opening, a holder movable through said opening beneath said sliding sash, a combined support and guide intermediate the upper and lower edges of said opening, on which said holder tilts and slides, for guiding said holder in its movement through said opening, the upper edge of said holder 10 swinging outwardly away from said sash, and the lower edge of said holder swinging inwardly beyond the lower edge of said opening, the holder then sliding inwardly 15 through said opening beneath the lower edge 20 of said sash.

6. The combination with a building construction having an opening therein lying in a substantially vertical plane, of vertical strips, one at each side of said opening, extending substantially from the bottom of 30 the opening half way up the side of the opening, and a holder extending substantially the full length of the opening and having two strips, one on each side thereof, for engaging with the upper ends of said first strips for tilting and sliding movement, the upper edge of said holder tilting outwardly and the inner edge of said holder 35 swinging inwardly until the lower edge of the holder clears the lower edge of the opening, the holder then sliding inwardly 40

through the opening, the lower portions of said second pair of strips engaging said first pair of strips to limit the outward movement of the lower part of the holder 45 when the display-holder is in display position.

7. The combination with a building construction having an opening lying in a substantially vertical plane, of a display-holder 50 lying in a plane substantially parallel with said opening when in display position and pivotally supported intermediate its ends to permit the upper end to swing out and the lower end to swing in to clear the bottom of said opening, said holder being also slidably supported to permit it to slide inwardly through the opening after the lower end has cleared the bottom of the opening.

8. The combination with a building construction having an opening therein, lying in a substantially vertical plane, of a holder movable through said opening, and a combined guide, support and a weatherproofing strip, located intermediate the upper and 65 lower edges of said opening, on which said holder tilts and slides, for guiding said holder in its movement through said opening, so that the upper edge of said holder swings outwardly and the lower edge of said 70 holder swings inwardly, to clear the lower edge of said opening, and then slides inwardly through said opening, the holder being provided with longitudinally extending slide portions for engagement with said 75 combined guide and support, said slide portions engaging said strip to form a weather-proof engagement when the holder is in position.

In witness whereof I have hereunto subscribed my name.

LEONARD G. QUACKENBOSS.
